Primary Examiner — Elizabeth J Oswecki(74) *Attorney, Agent, or Firm* — RG Patent Consulting, LLC; Rachel Gilboy(57) **CLAIM**

The ornamental design for the barefoot spike and cleat shoe, as shown and described.

DESCRIPTION

FIG. 1 is a perspective view of a barefoot spike and cleat shoe showing my new design;

FIG. 2 is a front side elevation view thereof;

FIG. 3 is a rear side elevation view thereof;

FIG. 4 is a right side elevation view thereof;

FIG. 5 is a left side elevation view thereof; and,

FIG. 6 is a bottom plan view thereof.

All surfaces not shown form no part of the claimed design. The broken lines shown in the drawings represent portions of the barefoot spike and cleat shoe that form no part of the claimed design.
